UNITED STATES PATENT OFFICE.

LAWRENCE E. McHUGH, OF DUBOIS, PENNSYLVANIA.

MAIL-CATCHER.

1,150,281.

Specification of Letters Patent. Patented Aug. 17, 1915.

Application filed March 28, 1914. Serial No. 827,972.

To all whom it may concern:

Be it known that I, LAWRENCE E. McHUGH, a citizen of the United States, residing at Dubois, in the county of Clearfield and State of Pennsylvania, have invented certain new and useful Improvements in Mail-Catchers, of which the following is a specification.

This invention relates to a mail catcher, and the principal object of the invention is to provide a mail catcher which is so constructed that a sack may be taken from a mail car and the catching arm swung to one side so that it will extend longitudinally of the track thus holding the mail sack out of the way; and to also provide an improved standard and support for the standard so that the standard may move pivotally against the tension of springs forming bumpers so that the standard may give when the sack is caught, and thus the arm and standard prevented from being bent or broken.

Another object of the invention is to so construct the supporting stand or frame that the bumper casing will be securely held in place, and the standard slidably connected with the frame with its piston extending into the casings to engage the springs which constitute the bumpers.

Another object of the invention is to so construct the mail catcher that the principal portions of the same may be formed from tubes or piping; thus permitting the mail catcher to be very cheaply manufactured and easily put together.

This invention is illustrated in the accompanying drawings wherein—

Figure 1 is a side elevation showing the mail catcher about to engage a sack extended from the car; Fig. 2 is a front elevation of the mail catcher with the sack-engaging arm swung to one side; Fig. 3 is a top plan view of the mail catcher with the sack-engaging arm in the position shown in Fig. 2; Fig. 4 is an enlarged perspective view of the sleeve which is mounted upon the standard and slidably connected with the frame; Fig. 5 is a fragmentary sectional view of the standard and bumper arrangement; Fig. 6 is a fragmentary view of the sack-holding device carried by the car.

The mail sack 10 is releasably connected with the clips 11 carried at the outer ends of the arms 12. These arms 12 are provided at their inner ends with collars 13 which are

mounted upon the sleeve 14. This sleeve 14 is rotatably mounted upon the bar 15 which has its upper ends connected with the mail car 16 at one side of the doorway so that the sleeve 14 may rotate to swing the arms 12 into and out of the car. A pin 16 is carried by the bar 15 and passes through a slot 17 formed in the sleeve 14 so that the rotary motion of the sleeve 14 will be limited and thus the inward and outward movement of the arms 12 controlled.

The standard 18 has its lower end pivotally connected with the pivot bracket 19 carried by the base 20. This base may be formed of any suitable material, but is preferably formed of cement or the like substance with the pivot bracket 19 either embedded therein or secured to the same by any suitable means. The frame 21 is supported by the legs 22 which have their lower ends embedded in the base 20. This frame and supporting legs are formed of pipe which are connected by couplings of the usual construction so that a rectangular frame shown clearly in Fig. 3 is provided with a support above the base as clearly shown in Figs. 1 and 2.

A collar 23 is carried by the standard 18 and is provided with arms 24 which are slidably mounted upon the side bars of the frame 21. Pistons 25 are pivotally connected with the pivot ears 26 of the collar 23 and are provided at their ends with heads 27 slidably mounted in the cylinders or casings 28. These casings 28 are supported by bands 29 carried by the frame 21 and contain springs 30 which engage the heads 27 of the pistons 25 so that the standard will be normally held in the upright position shown in the drawings. These springs permit the standard to move longitudinally of the frame with a swinging movement so that the force of a blow received when catching a mail sack may be taken up by the springs 30 and thus the standard prevented from being bent or broken.

The swinging arm 31 of the sack-engaging element is rotatably connected with the upper end portion of the standard by means of the sleeves 32 and rests upon the bar 33 formed upon the standard 18. Arms 34 extend from the sleeves 32 and support the clamps 35 which are intended to engage the swinging arm 31. Upon this arm 31 there is rotated a sleeve 36 which carries the sack-engaging jaws 37 yieldably held in a closed

position by the springs 38. Triggers 39 are carried by the jaws 37 and are adapted to releasably hold the jaws in an open position so that a mail sack may pass between the 5 jaws and engage the triggers to release the jaws and permit the springs 38 to close the same and grip the mail bag. In order to hold the sleeve 36 in a desired position upon the swinging arm 31, there has been provided set screws 40.

The operation of this device is as follows: The mail bag is suspended from the arm 12 by means of the catches 11 and the sack-engaging arm of the track device is swung out 15 to the position shown in Fig. 1. Before this arm is swung out to the position shown in Fig. 1, the sleeve 36 is adjusted so that the jaws will extend in the direction from which the train is approaching. When the train 20 passes the station, the sack will pass between the jaws and release the triggers 39 so that the jaws will close upon the sack and release the same from the catches 11. The force of the blow received when the sack strikes the 25 catching arm will swing the arms around in engagement with one of the clamps 35, and the arm will thus be held in the position shown in Fig. 2 with the arm extending longitudinally of the track. The force of 30 this blow will put the standard 18 in motion and cause it to rock upon its pivot bracket 19, thus successively compressing the springs 30 mounted in the casings or cylinders 28. This swinging motion will greatly decrease 35 until the springs return the standard to the vertical position. It will thus be seen that the swinging arm and standard will not receive the full force of the blow given by the mail bag, but that the force of this blow 40 will be taken up by the spring 30, thus preventing the swinging arm and standard from being bent or broken. If the train is approaching from the opposite direction, it is simply necessary to release the set screws 45 40, turn the sleeve 36 upon the swinging arm 31, and then tighten the set screws again so that the jaws will extend in the direction from which the train is approaching. It will thus be seen that the same track device 50 may be used for catching sacks from trains moving in two different directions.

I claim—

1. A mail catcher comprising a frame, a pivotally-mounted standard, supporting 55 means for said standard slidably connected

with said frame, cylinders carried by said frame, pistons connected with said supporting means and extending into said cylinders, resilient means in said cylinders engaging said pistons to yieldably hold said standard 60 in a vertical position, and catching means carried by said standard.

2. A mail catcher comprising a frame, a pivotally-mounted standard, means slidably connecting said standard with said frame, 65 cylinders carried by said frame upon the opposite sides of said standard, springs mounted within said cylinders, pistons extending from the means slidably connecting said standard with said frame and extending into said cylinders and engaging the springs mounted therein to yieldably hold said standard in a vertical position, and catching means carried by said standard.

3. A mail catcher comprising a frame, a 75 movably mounted standard, means slidably connecting said standard with said frame, cylinders carried by said frame, pistons extending from said last-mentioned means into said cylinders, resilient means in said cylinders 80 engaging said pistons to yieldably hold said standard in a vertical position, and catching means carried by said standard.

4. A mail catcher comprising a frame, a 85 movably-mounted standard, a collar slidably mounted upon said standard and slidably connecting said standard with said frame, cylinders carried by said frame, pistons extending from said collar into said cylinders, resilient means in said cylinders 90 engaging said pistons to yieldably hold said standard in a vertical position, and catching means carried by said standard.

5. A mail catcher comprising a frame, 95 supporting means for said frame, a movably-mounted standard, a collar carried by said standard and slidably connected with said frame, cylinders carried by said frame, pistons extending from said collar into said cylinders, resilient means in said cylinders 100 engaging said pistons to yieldably hold said standard in a vertical position, and catching means carried by said standard.

In testimony whereof I affix my signature in presence of two witnesses.

LAWRENCE E. McHUGH.
